ratories, Incorporated, Chicago, Ill., a corpora-
tion of Illinois

Application December 27, 1937, Serial No. 181,905

15 Claims. (Cl. 237—81)

This invention relates to a method of utilizing combustion gases containing sulphur in, for example, heating systems or in power plants; and the primary object of the invention is to provide a new and improved method for the utilization of such gases which will prevent corrosion of surfaces with which such gases come into contact, such as metal surfaces, for instance, by insuring the dilution of sulphuric acid in the condensate to a point at which the acid is substantially non-corrosive.

The invention has for one of its particular objects, the prevention of corrosion in a heating system of the type in which the heating medium consists of a mixture of the products of combustion of fuel gas, oil or coal, and water vapor; the invention being of special value in a system in which the temperature of the heating medium in its circulation through the radiating system is reduced to give a low outlet flue temperature for the purpose of effecting economy of operation. In heating systems using combustion gases containing water vapor resulting from combustion, or such water vapor plus water vapor added to the products of combustion, it has been found necessary to circulate and exhaust the heating medium at wastefully high temperatures in order to prevent condensation and the formation of strong sulphuric acid, as the heat in these gases is given up in the system at certain intermediate temperature ranges, with consequent corrosion or deterioration of piping and other metal parts. Heating systems employing such mixtures as their heating media have not always proved economical, efficient, or entirely practical for this reason. That is, as the heating medium progresses through the system it loses heat and at certain temperatures, within the range say of 175° to 135° F., depending upon the amount of atmospheric gases and the amount of sulphur in the fuel, and unless the water content of the medium is properly regulated (as proposed by the present invention) condensation will take place in the form of relatively strong sulphuric acid, such as 30 to 90% acid, which will have a corrosive action, not only on iron but even on copper and metallic alloys ordinarily regarded as relatively non-corrosive as well as on other materials such as common flue materials. As the temperature of the medium is still further reduced below the strong acid dew point, a temperature range will ultimately be reached at which water will condense in such excess as to prevent appreciable corrosion. But at places in the system in advance of this, where medium

temperatures prevail, condensation of strong acid and consequent corrosion are, under the conditions assumed, practically always sure to take place, provided the gas or other fuel contains any substantial quantity of sulphur, as is the case with oil, coal and most manufactured fuel gases.

In accordance with the present invention, corrosion is prevented by adding to the combustion gases a relatively large quantity of water vapor so that wherever condensation of acid takes place, the water will be in such excess over the sulphur compounds condensing out at the same time that the latter will be diluted to a substantially non-corrosive state. By constantly insuring a mixture of this character, it is possible to reduce outlet flue temperatures to such a degree as to make this type of heating process very practical and economical. Preferably the system will be operated under a slight vacuum, say a fraction of an inch of mercury for two purposes: first, to insure against escape of gases from the system into rooms in case of leakage; and second, because the corrosive effect of such acid as there may be in the condensate is enhanced by increase of pressure and temperature. The initial temperature of the heating medium, as it comes from the generator and enters the heating system, will ordinarily be between 190° and 212° F. and the outlet flue temperature between 100° F. and 120° F. The dew point depends upon three factors: the amount of sulphur, sulphur raising the dew point; the amount of air in the mixture which tends to lower the dew point, but the presence of which decreases efficiency; and the amount of water vapor present, which latter will be the sum of the water produced by combustion and that added at the generator. The water added at the generator is, of course, the dew point controlling factor, in accordance with the present invention; and in order to insure against corrosion it has been found necessary, under ordinary practical conditions to increase the water vapor content of the medium so that the resulting condensate will not contain at any time more than a fraction of 1% of sulphuric acid. In order to be as safe as possible, it is desirable to have the medium saturated at approximately atmospheric pressure and at an initial temperature of 190° to 212° F. This, however, is not ordinarily essential, and initial saturation at about 175° F., or even somewhat lower, will be sufficient if a fuel gas is used containing 25 grains of sulphur per 100 cubic feet, or other fuels with usual

sulphur contents. Under ordinary conditions the amount of water vapor in the medium at 190° F. should be from 25%, by volume, up to saturation.

5 The application of the invention to practice is illustrated in the accompanying drawing which is a diagram of a heating system suitable for practicing the process of this invention.

Referring to the drawing, 1 designates the generator which is shown diagrammatically but is not claimed herein being claimed in copending application, Serial No. 183,048, filed January 3, 1938, now Patent No. 2,169,683, granted August 15, 1939. The generator is formed with a water

10 space 2, and a combustion chamber 3 in which is located a burner 4, supplied by gas pipe 5. The products of combustion pass through ducts 6 and 7, where they are mixed with water which is forced from space 8 through ducts 9 into the re-

15 ceptacle 10 over the edge of which the water flows into the upwardly moving current of combustion gases. The mixture containing the proper quantity of water vapor, in accordance with the principles of the invention hereinabove set forth, (in-

20 sured by the use of a generator as described which operates in fact to give substantial saturation at 190°-212° F.) passes through the supply main 11 to the radiators 12-12, the radiators being connected to the supply main by risers 13-13 and to

25 the return main 14 by down pipes 15-15. A water seal 16 may be interposed between the supply main and return main. The return main 14 is connected with an exhauster 17, the eduction pipe 18 of which constitutes the vent pipe of the

30 system. Leading from the return main is a condensate return pipe 19 which is connected with the water space of the generator at 20 and with a pipe 21 connected with supply main 11 and having therein an overflow pipe 22 which through

35 water seal 23 delivers into drain pipe 24. A pipe 25, having a water seal 26, may connect the exhauster with drain pipe 24. Under ordinary conditions of operation, the water produced by combustion will be sufficient for the needs of the sys-

40 tem with some excess which passes out through pipe 24. Additional water may be introduced into the system, automatically or otherwise, from pipe 27: or the returned water might be chemically

45 treated to reduce acidity.

50 In the preferred operation of the system as disclosed, the exhauster and gas supply will be automatically controlled by a room thermostat 28, this specific control mechanism, however, forming no part of the present invention. However,

55 the use of such a thermostatic control results in the intermittent use of the generator, that is the combustion process is started and stopped at rather short intervals. Consequently it is necessary that a generator be used which will start the

60 vaporizing and saturating process almost immediately after the combustion process has been restarted so that there will be no substantial periods of time in which the combustion gases will be insufficiently saturated. The generator

65 herein diagrammatically disclosed, and disclosed more in detail in said copending application, is particularly adapted for this purpose.

The outflow through pipe 24 will ordinarily be sufficient to keep the acid from building up in the

70 system. It will also be understood that the water formed in the combustion process offsets the acid formed so as to continuously dilute the acid solution. If necessary additional water for this purpose may be introduced into the system from pipe

75 27.

In carrying out the invention in its preferred form, it is the aim to maintain relatively low stack temperature, temperatures far below the dew point for the water vapor from the gas, so that the latent heat in the water vapor is utilized and the water recovered for reuse. To accomplish this purpose the combustion gases are saturated at the generator sufficiently so that any sulphuric acid formed at any place in the system will be so dilute as to be incapable of bringing about to any appreciable extent corrosion or other deterioration of the surfaces with which the gases and condensate come into contact in the system.

It is the intention to cover by patent all equivalents of the herein disclosed method of operation and all modifications thereof within the scope of the hereto appended claims.

We claim:

1. Method of utilizing combustion gases containing sulphur in such manner as to prevent corrosion or deterioration of surfaces with which said gases come into contact which comprises: adding to the combustion gases such a relatively large quantity of water vapor that at all places where condensation takes place water will be in excess of sulphuric acid to dilute the acid to a substantially non-corrosive condition. 20

2. Method of utilizing combustion gases containing sulphur in such manner as to prevent corrosion or deterioration of surfaces with which said gases come into contact which comprises: adding to the combustion gases such a relatively large proportion of water vapor that the resulting water of condensation from the mixture of gases 30 will contain less than 1% of sulphuric acid. 35

3. Method of utilizing combustion gases containing sulphur in such manner as to prevent corrosion or deterioration of surfaces with which said gases come into contact which comprises: 40 adding to the hot combustion gases water vapor, which, at temperature of 190°-212° F. will constitute from 25%, by volume, to saturation of the mixture.

4. Method of heating which comprises: circulating through a radiating system combustion gases containing sulphur; and mixing therewith water vapor in such quantity that at all places where condensation takes place, water will be sufficiently in excess over sulphuric acid to dilute 45 the acid to a substantially non-corrosive condition. 50

5. Method of heating which comprises: circulating through a radiating system combustion gases containing sulphur; and mixing therewith water vapor in such quantity that the water of condensation will contain less than 1% of sulphuric acid. 55

6. Method of heating which comprises: circulating through a radiating system combustion 60 gases containing sulphur; and mixing therewith water vapor which calculated at a temperature of 190°-212° F. will consist of between 25% and 50% of the volume of the mixture.

7. Method of heating which comprises: circulating through a radiating system at an initial pressure slightly below atmospheric pressure and at an initial temperature of between 190° and 212° F., combustion gases containing sulphur and also containing water vapor in such quantity that at all places where condensation takes place water will condense in sufficient excess over sulphuric acid to dilute the sulphuric acid to a substantially non-corrosive condition. 70

8. Method of heating which comprises: circu-

lating through a radiating system at an initial pressure slightly below atmospheric pressure and at an initial temperature of between 190° and 212° F., combustion gases containing sulphur and 5 also containing water vapor in such quantity that the mixture is substantially saturated as it enters the radiating system.

9. Method of heating which comprises: circulating through a radiating system at an initial 10 pressure slightly below atmospheric pressure and at an initial temperature of about 190°-212° F. a mixture of combustion gases containing sulphur and from 25% to 50%, by volume, of water vapor.

10. Method of heating which comprises: circulating 15 through a radiating system at a slight vacuum and an initial temperature of 190°-212° F. which is reduced to a flue temperature of 100°-120° F., a mixture of combustion gases, containing sulphur, and a water vapor in such quantity 20 that the condensate contains less than 1% of sulphuric acid.

11. Method of heating which comprises: circulating 25 through a radiating system a mixture of flue gases, containing sulphur, and water vapor, which mixture is substantially saturated at the entering temperature of said mixture.

12. Method of forming and utilizing for heating 30 purposes a gaseous medium comprising combustion gases containing sulphur, which method comprises lowering the initial temperature of the medium by transferring to a body of water a portion of the heat from the combustion gases directly after the combustion process to convert this water to water vapor which is immediately 35 added to the combustion gases in sufficient quantity so that at all places where condensation takes place water will dilute the sulphuric acid to a substantially non-corrosive condition.

13. Method of forming and circulating through 40 a radiating system a gaseous medium comprising combustion gases containing sulphur, which method comprises lowering the initial tempera-

ture of the medium by transferring to a body of water a portion of the heat from the combustion gases directly after the combustion process to convert this water to water vapor which is immediately added to the combustion gases in sufficient quantity so that at all places where condensation takes place water will dilute the sulphuric acid to a substantially non-corrosive condition, the medium being formed and circulated under sub-atmospheric pressures by exhausting 5 the non-condensable portion of the medium from the radiating system.

14. Method of forming and utilizing for heating 10 purposes a gaseous medium comprising combustion gases containing sulphur, which method 15 comprises lowering the initial temperature of the medium by transferring to a body of water a portion of the heat from the combustion gases directly after the combustion process to convert this water to water vapor which is immediately 20 added to the combustion gases to form a mixed fluid heating medium having an initial temperature between 190° and 212° F. and containing water vapor in sufficient quantity so that at all 25 points where condensation takes place water will dilute the sulphuric acid to a substantially non-corrosive condition.

15. Method of forming and utilizing for heating 30 purposes a gaseous medium comprising combustion gases containing sulphur, which method 35 comprises lowering the initial temperature of the medium by transferring to a body of water a portion of the heat from the combustion gases directly after the combustion process to convert this water to water vapor which is immediately 40 added to the combustion gases to form a mixed fluid heating medium having an initial temperature between 190° and 212° F. and containing from 25% to 50% by volume of water vapor.
